SPLICER

Charles N. Replogle, Johnstown, Pa., assignor to
 Flood City Brass & Electric Company, Johnstown, Pa., a corporation of Pennsylvania

Application April 1, 1935, Serial No. 14,059

4 Claims. (Cl. 191—44.1)

My invention relates to splicers and, in particular, to splicers for wires, such as trolley wires.

It is desirable that trolley wire splicers be adapted for suspension from an overhead support and while splicers known heretofore have been provided with such means, all of them with which I am familiar have required a special type of support for the splicer, in addition to that usually employed for suspending the trolley wire itself.

10 It is an object of my invention, therefore, to provide a trolley wire splicer having means whereby it may be suspended from a standard trolley wire suspension hanger of any convenient type, therefore making unnecessary any special hanger

15 for the splicer.

Other novel features of my invention will become apparent as the description thereof proceeds and will be particularly pointed out in the appended claims. For a complete understanding 20 of the invention, reference is made to the accompanying drawing illustrating a preferred embodiment thereof. In the drawing:

Figure 1 is a side elevation partly broken away;
 Figure 2 is a plan view;

25 Figure 3 is a transverse sectional view; and
 Figure 4 is a side elevation similar to Figure 1 showing the splicer with wires secured therein and suspended by a standard trolley wire hanger; line III—III of Figure 4 indicates the plane on 30 which the sectional view of Figure 3 is taken.

The splicer of my invention indicated generally at 10 preferably comprises a one-piece bronze casting having a bottom bar 11, end sleeves 12 and 13, and a top bar 14. The end sleeves 12 and 13 and the bottom bar 11 are cored out to provide a passage 15 for wires inserted through the former. The passage may be dimensioned to receive any desired size of wire, but it is not necessary that the size of the passage conform closely 35 to that of the wire. Set screws 16 threaded into bosses 17 formed between the top bar 14 and the end sleeves 13 are tightened up against the ends of the wires after they have been inserted through the sleeves 12 and 13 to secure them in place.

40 As shown in Figure 3, the bottom bar 11 is of substantially U-shape in cross section and the passage 15 is larger than the wires adapted to be joined by the splicer. The space between the wires and the bottom bar or the end sleeves is preferably filled with solder, as indicated at 16a, by pouring it while molten into the groove in the upper face of the bottom bar 11, whence it flows into the end sleeves 12 and 13 and secures the 45 ends of the wires firmly therein, and also pro-

vides a good electrical contact between the wires and splicer.

The ends of the sleeves 12 and 13 are provided with V-shaped slots 18. By milling out the ends of the sleeves to form the slots, I prevent bumping of the trolley against the ends of the splicer, since the trolley wheel rides easily from the wire onto the tapering sides of the end sleeves and does not strike a direct blow against the ends of the splicer. The slots cause the engagement of 10 the trolley with the end of the splicer to have the effect of a glancing blow so that very little shock is imparted either to the trolley or the splicer.

The top bar 14, as shown in Figure 3, has the same size and shape as a standard trolley wire. 15 By making the top bar 14 of the same size and shape as a standard trolley wire, I am able to employ a standard trolley suspension hanger, such as that shown at 19, for supporting the splicer from above. Since any standard type of trolley 20 wire suspension may be employed, it is unnecessary to go into the details of construction of any particular hanger. These hangers are a standard article and are available at relatively low cost. This feature of the invention is particularly ad- 25 vantageous in reducing the cost of overhead trolley installation and maintenance, since it avoids the necessity for providing a special type of hanger for the splicer, which has always been necessary heretofore, or the use of a pair of trolley 30 clamps, one on each side of the splicer and comparatively close thereto. The advantage of rigidly supporting the splicer, obviously, is that whatever force is exerted thereon by the trolley is then unable to cause bouncing or swinging of 35 the splicer.

The bosses 17 are liberally dimensioned so as to prevent the possibility of stripping the threads thereof in tightening of the set screws 16, which is a common fault with previous splicers. The 40 top bar 14 is given a partial twist, as shown in Figure 2, to permit the ends of the wires to be joined to be pulled out and bent upwardly, as shown in Figure 4.

45 Although I have illustrated and described herein but one preferred embodiment of the invention, it will be obvious that changes therein may be made without departing from the spirit of the invention or the scope of the appended claims. If grooved or so called "figure eight" trolley wire, 50 for example, is employed, the top bar may be grooved similarly to accommodate the suspension clamps designed particularly to support grooved trolley wire, or a top bar such as that shown may 55

be used in cooperation with hanger clamps designed for round wire.

I claim:

1. The combination with a trolley wire splicer having end sleeves connected by a bottom bar, said sleeves and bar forming a passage for wires, means for securing the ends of said wires to said splicer and a top bar also connecting the end sleeves, of a trolley wire clamp engaging said top bar.
2. The combination defined by claim 1 characterized by said sleeves being adapted to receive wires of at least the size of said top bar.

3. The combination with a trolley wire splicer comprising a bottom bar, end sleeves thereon, and a round top bar, integral with said bottom bar and sleeves, emerging gradually from the sleeves, extending substantially parallel to the bottom bar and connecting said end sleeves, of a standard trolley wire clamp engaging said round top bar.

4. The device defined by claim 3 characterized by said bottom bar being open upwardly between said sleeves to permit solder to be poured therein around the ends of wires entering the sleeves.

CHARLES N. REPLOGLE.
